Letters Patent No. 2089. Dated June 18, 1866.

Design for a Trade Mark.

The schedule referred to in these Letters Patent and making part of the same
shall whom it may concern:

Be it known that A. G. Goodnow, of the
City, County and State of New York, have invented and improved
Design for a Trade Mark, and I hereby declare that the following is
a full, clear and exact description thereof, which may be made by one
skilled in the art to make and use the same, referring to the said
to the accompanying drawings forming part of this specification.

This invention relates to an ornamental de-
sign to be stamped upon cutlery to constitute a trademark.

The drawing is an elevation of a portion of the
blade and handle of a knife upon the blade of which any design is
stamped.

My improved design or trade mark consists
of an ornamental figure of an anchor arranged and represented in
the ornamental manner shown which design is to be stamped
or otherwise affixed upon the blade or other portion of the cut-
lery or other article.

Having thus described my invention I claim as new
and desire to secure by Letters Patent.

The ornamental design for a trade mark herein
shown and described.
